CLAIM

The ornamental design for a detachable saddle bag, as shown and described.

DESCRIPTION

FIG. 1 is a top right side perspective view of a detachable saddle bag showing a new design attached to a golf bag; FIG. 2 is a top left perspective view of the detachable saddle bag as shown in FIG. 1 attached to the golf bag with a shoulder strap attached to the golf bag;

FIG. 3 is a top right perspective view of the detachable saddle bag as shown in FIG. 1 that can be attached to and detached from a golf bag;

FIG. 4 is a front side plan view of the detachable saddle bag as shown in FIG. 3;

FIG. 5 is a rear side plan view of the detachable saddle bag as shown in FIG. 3;

FIG. 6 is a left side plan view of the detachable saddle bag as shown in FIG. 3;

FIG. 7 is a right side plan view of the detachable saddle bag as shown in FIG. 3;

FIG. 8 is a top plan view of the detachable saddle bag as shown in FIG. 3; and,

FIG. 9 is a bottom plan view of the detachable saddle bag as shown in FIG. 3.

In the drawings, the shorter dash broken lines with shorter spacing are for the purpose of illustrating certain stitching that do not form part of the claimed design. The longer dash broken lines illustrating a golf bag represent environment that forms no part of the claimed design.

The longer dash broken lines on the surface of the detachable saddle bag represents portions of the article that form no part of the claimed design.
